G. S. RIDER.

MANTLE BURNER FOR KEROSENE LAMPS.

APPLICATION FILED OCT. 26, 1910.

1,022,700.

Patented Apr. 9, 1912.

UNITED STATES PATENT OFFICE.

GRANVILLE S. RIDER, OF NEW YORK, N. Y.

MANTLE-BURNER FOR KEROSENE-LAMPS.

1,022,700.

Specification of Letters Patent. Patented Apr. 9, 1912.

Application filed October 26, 1910. Serial No. 589,095.

To all whom it may concern:

Be it known that I, GRANVILLE S. RIDER, a citizen of the United States, residing at the borough of Manhattan, city of New York, in the county of New York and State of New York, have invented certain new and useful Improvements in Mantle-Burners for Kerosene-Lamps, of which the following is a specification, reference being had therein to the accompanying drawings, forming part thereof.

My invention relates to mantle burners for kerosene lamps and has for its general object the securing of better combustion of the vaporized oil, thereby obtaining a brighter light and avoiding blackening the mantle.

More particular objects of my invention are to more effectively direct the air outward to the point of initial combustion from the top of the inner wick tube, to more thoroughly intermix the air and vapor, to more uniformly distribute the mixture to the inner surface of the mantle and to prevent overheating of the inner wick tube, the heat being utilized instead to preheat the air supplied through the inner wick tube.

Lamp burners of the type to which my invention is applicable have been objectionable by reason of imperfect combustion resulting in only partial incandescence of the mantle and also at times in blackening of the mantle by carbon deposits. This imperfect combustion is commonly due to an unbalanced or unequalized condition or relation in which more vapor is produced than is consumed. I have found that two principal causes of this defect are, first, the overheating of the inner wick tube, by reason of the fact that usually a necessarily highly heated burner cap is supported in direct contact with the upper portion of the inner wick tube and from which the intense heat at the point of initial combustion is conducted downward along the wick tube, causing excessive formation of vapor; and, second, the failure to properly direct a sufficient supply of air to the seat of combustion, particularly to the upper part of the mantle, where combustion has been particularly poor or imperfect.

My invention is directed to providing an improved air distributor for the inner wick tube by reason of the operation of which, in combination with other parts of the

burner, the air will be thoroughly mixed with the vapor and the mixture substantially equally distributed to all parts of the mantle.

My invention includes an upwardly flaring or inverted cone-shaped air distributor or spreader located within the inner wick tube and extending into proximity to the seat of primary or initial combustion, so that the draft of air passing upward through the inner wick tube is deflected outwardly and uniformly directed to the seat of combustion.

My invention also includes means upon the air distributor for producing whirls or eddies of air adjacent to the point of initial combustion to thereby secure a better intermixing or commingling of the air and vapor.

My invention also includes supporting means for an air distributor, providing a minimum heat conductive connection with the other part of the burner, thereby substantially obviating the conductance of heat from the highly heated air distributor back down the inner wick tube, such heat instead being given up to the incoming air, which is thus more effectively preheated.

I shall now describe my invention with reference to the accompanying drawings illustrating two embodiments thereof and shall thereafter point out my invention in claims.

Figure 1 is a partial central vertical section of a lamp embodying my invention, the top portion of the chimney being omitted. Fig. 2 is a plan view of the air distributor for the inner wick tube. Fig. 3 is an elevation of the same. Fig. 4 is an inverted plan view of the same. Fig. 5 is a partial central vertical section of a slightly modified lamp burner with portions omitted.

In Figs. 1 to 4, inclusive, of the drawings, my invention is shown as embodied in a central draft lamp, that is to say, in a lamp in which the inner wick tube passes through the bowl or font of the lamp, and the draft of air supplied through such inner wick tube enters at the open lower end thereof below the font.

In Fig. 5 my invention is shown as embodied in a side draft burner, that is to say, in a burner having an inner wick tube which is closed at the lower end and is provided with a lateral air inlet.

In the embodiment of my invention illus-

trated in Figs. 1 to 4, inclusive, of the drawings, a burner is shown having a lower part or base 1 provided with a wick-adjusting means as indicated by the handle 2 and having air-inlet openings as shown; and an upper part 3 shown as fitting over the base 1 and provided with usual spring chimney supports 4 for holding in place a chimney 5. The burner is shown as applied to a lamp font 6 having a base 7, both font and base being of usual construction. Outer and inner wick tubes, 8 and 9, respectively, are provided, carried respectively by the burner base 1 and by the lamp font 6, as usual in this type of lamp, the inner wick tube 9 passing through the font 6 and being open at its lower end below the font, so that air entering at the lower end of the inner wick tube passes up through the inner wick tube to the inside of the circular flame, a wick 10 being contained between the inner and outer wick tubes. The outer wick tube 8 is of usual construction and is provided at its upper end with a radial flange as shown.

25 A gallery 11 surrounds the outer wick tube 8 and extends above the upper end of the outer wick tube and is provided at its top with an inwardly turned flange overlying the flange of the outer wick tube 8, the gallery 11 being shown as formed integral at its base with the upper part 3 of the burner. A mantle 12 is supported in the usual manner above the gallery 11 and outer and inner wick tubes 8 and 9 by a supporting wire 13 extending upwardly from a socket 14 carried by the upper part 3 of the burner. The inner wick tube 9 is also of usual construction with the exception that it is provided at the proper location for the purpose with an internal annular bead or ridge 15 for supporting an air distributer, to which, in combination with the other parts of the lamp, my invention is chiefly directed.

40 My improved air distributer will now be described, it being, of course, understood that the construction of the hereinbefore described parts of the device of usual construction may be varied within certain practical limits and still be coöperative with the 45 improvements introduced by my present invention.

The illustrated embodiment of the air distributer for distributing the draft of air passing upward through the inner wick tube 55 includes upwardly diverging imperforate walls forming an inverted hollow cone 16, which extends from within the inner wick tube 9 into proximity to the seat of initial and partial combustion and is shown as terminating at a plane above the upper ends of the wick tubes 8 and 9 and slightly above the inwardly turned flange of the gallery 11, such cone providing an upwardly and outwardly flaring air-directing outer 60 surface which is spaced from the upper end of

the inner wick tube to form an annular air outlet between the upwardly flaring wall of the air distributer and the inner wick tube, so that the ascending stream of air is strongly deflected outwardly and is uniformly directed to the seat of combustion. The cone 16 directs the air outwardly just above the top of the inner wick tube 9 and at a point below the inwardly turned flange of the gallery 11. The current of air deflected outwardly by the cone 16 meets another current of air deflected inwardly by the flange of the gallery 11, so that the air and vapor become thoroughly and uniformly mixed. To obtain a better mixing together of the air and combustible vapor, I have provided means for producing whirls or eddies of air and vapor adjacent to the seat of initial combustion. For this purpose, the outer and upper marginal portion of the wall of the cone 16 is turned to form an annular semi-circular groove 17, the outer transversely concave surface of which produces the required intermixing movements in the passing annular air column. This eddy producing intermixing function is enhanced and additional advantageous results are secured by a disk 18 located concentrically above and spaced upwardly from the open upper end of the inverted hollow cone 16. The disk 18 is shown as slightly concave at its upper side and as having an annular series of perforations. This disk is shown as supported on the cone 16 by slender supporting columns 19 extending between the marginal portions of the disk 18 and of the cone 16. The annular ascending air column, in passing the edges of the disk 18 and cone 16 and the open space between such edges, is subjected to a further eddy producing and intermixing effect, and some of the air will enter between such edges and then pass upward through the perforations in the disk 18. Because of the fact that the air deflecting surfaces of the cone 16 are below the top of the gallery 11, the mixture of air and vapor passing upward between the inwardly turned flange of the gallery 11 and the top of the cone 16 will be directed for the most part upwardly and only slightly outwardly and will be substantially uniformly distributed to the entire inner surface of the mantle, where final incandescence producing combustion takes place, the entire mantle thus being rendered brilliantly incandescent. In lamps as heretofore commonly constructed the air has been directed outwardly above a gallery, corresponding to the gallery 11, and is thrown directly outward substantially horizontally against the lower part only of the mantle, the result being not only a poor mixing of the air and vapor, but incandescent combustion at the lower part only of the mantle, the upper parts quickly becoming blackened by carbon deposits. The

foregoing explanation has made it clear how my invention effectively overcomes this imperfection.

The parts of the air distributor so far described will, as a result of proximity to the seat of combustion above the wick tubes, become highly heated, and a large amount of this heat will be conducted downward to the portions of the air distributor that are located within the inner wick tube. In the construction of lamps heretofore commonly employed, the intense heat of the air distributor, or burner cap, as the corresponding part is sometimes called, is conveyed directly by conduction to the inner wick tube, by which it is conducted farther downward and by which such heat is transmitted directly to the oil in the wick and thereby produces, as hereinbefore noted, the formation of vapor in excess of what can be burned.

I will now describe the means devised by me whereby the necessarily intense heat of the air distributor is substantially all kept away from the inner wick tube 9 and is caused to be given up to the draft of air supplied through the inner wick tube to more effectively preheat this air, such means consisting of supports for the air distributing cone 16 and the parts carried thereby, which substantially thermally insulate the air distributor from the inner wick tube and other parts of the burner. These supports are shown as prongs or slender legs 20, projecting divergently downward from the lower end or apex of the cone 16. The prongs 20 are shown as made of flat material and the upper ends of these prongs are bent and curved to fit within a reduced cylindrical lower portion 21 of the cone 16, in which they are shown as clamped in place by a cup-shaped hollow plug 22, which completes the closure of the lower end of the cone 16. The prongs 20 are shown as three in number and at their lower divergent free ends are tapered to points which are adapted to rest, as shown in Fig. 1, on the annular bead or ridge 15 of the inner wick tube 9. The pointed ends of the prongs 20 constitute the only connection between the air distributor and the other parts of the lamp. Besides the substantial amount of thermal insulation afforded by this connection, it should be noted that the current of cool incoming air, passing in contact with the slender prongs 20, will abstract the greater portion of any heat which they may receive from the cone 16, such heat serving the useful purpose of preheating such incoming cool air. However, a very substantial preheating of the air takes place by reason of the quite considerable amount of heat communicated thereto by the air-deflecting cone 16. Substantially all of the heat taken up by the cone 16 and disk 18 is transmitted to the incoming air to effectively preheat the same

and thereby produce better combustion. It is therefore to be seen from the foregoing description of this illustrated embodiment of my invention that the unbalanced relation between the rapidity of vapor production and the quantity of properly preheated air supplied through the inner wick tube has been very largely, if not completely, compensated for and corrected.

In Fig. 5, means embodying my invention are shown as modified for application to a slightly different type of burner. In this type of burner the inner and the outer wick tubes 23 and 24, respectively, are both carried by the burner base 25, the lower end of the inner wick tube 23 is closed by the disk 26, and the inner wick tube 23 is provided with a lateral air inlet 27 extending through both wick tubes at the side, and air entering through the inlet 27 passes upward inside the inner wick tube 23 to the inside of the circular frame. In burners of this type, it is common to support the air distributor or air deflector (sometimes called a spreader) upon a post projecting upward from the bottom closure of the inner wick tube, and I have shown such a usual post 28 as carried by and projecting upward from the bottom closure 26, such post 28 being steadied by a brace 29 in substantially the usual manner. In this form of my invention the air distributor has a tube 30 adapted to slip over the post 28, as shown. At the proper height the tube 30 carries an air-directing cone 31 of substantially the same construction and function as the corresponding cone 16 hereinbefore described. At its upper end the tube 30 carries a dished and perforated disk 32, which is spaced a short distance upwardly from the upper end of the cone 31 and which corresponds substantially to the disk 18 hereinbefore described. The substitution of the tube 30 for the pointed prongs or legs 20 adapts my improved air distributor for application to this other type of burner already found on the market, while still retaining in great measure the advantageous results of my invention hereinbefore set forth.

It is obvious that various modifications may be made in the constructions shown in the drawings and above particularly described within the principle and scope of my invention.

I claim:

1. A mantle burner having, in combination with inner and outer wick tubes and a gallery surrounding the outer wick tube and rising above the wick tubes, an air distributor comprising an inverted cone located partly above and partly below the top of the inner wick tube and having an upwardly diverging outer air-directing surface extending upwardly from a point within the inner wick tube and terminating sub-

- stantially at the level of the top of the gallery.
2. A mantle burner having, in combination with inner and outer wick tubes and a gallery surrounding the outer wick tube and rising above the wick tubes, an air distributer comprising upwardly diverging imperforate walls forming an inverted hollow cone having a closed downwardly directed apex and extending from within the inner wick tube to substantially the level of the top of the gallery, and downwardly diverging supporting prongs projecting downwardly and outwardly from the apex of the inverted cone, such prongs having pointed free ends engaging the inner side of the inner wick tube, such points supporting the air distributer and constituting the sole connection of the air distributer with other parts of the burner. 65
3. An air distributer for a mantle burner having an inner wick tube, such distributer comprising upwardly diverging imperforate walls forming an inverted hollow cone having a closed downwardly directed apex and extending from within the inner wick tube upwardly into proximity to the seat of combustion and providing an upwardly and outwardly flaring air-directing outer surface spaced from the upper end of the inner wick tube to form an annular air outlet, and a disk located concentrically above and spaced upwardly from the open upper end of the inverted hollow cone. 70
4. An air distributer for a mantle burner having an inner wick tube, such distributer comprising an inverted cone extending from within the inner wick tube upwardly into proximity to the seat of combustion and providing an upwardly and outwardly flaring air-directing outer surface spaced from the upper end of the inner wick tube to form an annular air outlet, a marginal eddy-producing groove being formed laterally at the outside of the upper and larger end of the cone. 75
5. The combination, in a mantle burner having an inner wick tube, of an air distributer for the inner wick tube, and pointed supports the points of which are adapted to make contact with the inner wick tube and form the only supporting means for the air distributer and which also form the only connection between the air distributer and the other parts of the burner. 80
6. A kerosene mantle burner having, in combination, an inner wick tube provided with an internal unevenness, and an air distributer provided with pointed supports the points of which rest upon such unevenness. 85
- and which constitute the sole supporting means of the air distributer, the supporting points also constituting the sole connection between the air distributer and the other parts of the burner. 90
7. A kerosene mantle burner having, in combination with inner and outer wick tubes and a gallery surrounding the outer wick tube and rising above the wick tubes, an air distributer comprising an inverted cone extending from within the inner wick tube upwardly and terminating substantially at the level of the top of the gallery and providing an upwardly and outwardly flaring air-directing outer surface extending from below the top of the inner wick tube to the top of the gallery and spaced from the top of the inner wick tube to form an annular air outlet, and downwardly diverging supporting prongs projecting downwardly and outwardly from the apex of the inverted cone, such prongs having pointed free ends engaging the inner side of the inner wick tube to thereby support the air distributer, these points constituting the sole connection of the air distributer with other parts of the burner. 95
8. A kerosene mantle burner having, in combination, an inner wick tube provided at its inner side with an unevenness adapted to support an air distributer, and an air distributer comprising upwardly diverging imperforate walls forming an inverted hollow cone having a closed downwardly directed apex and extending from within the inner wick tube upwardly into proximity to the seat of combustion and providing an upwardly and outwardly flaring air-directing outer surface spaced from the upper end of the inner wick tube to form an annular air outlet, the upper and outer marginal portion of the cone being turned to form at the outside of the cone an annular substantially semi-circular groove providing an air-deflecting eddy-producing surface, an air-deflecting and eddy-producing disk located concentrically above and spaced upwardly from the open upper end of the inverted hollow cone, and downwardly diverging supporting prongs projecting downwardly and outwardly from the apex of the inverted cone, such prongs having pointed free ends engaging such unevenness. 100
